[57] CLAIM

The ornamental design for a phonograph cabinet, as shown and described.

DESCRIPTION

FIG. 1 is a top side perspective view of a phonograph cabinet showing my new design;

FIG. 2 is a front elevation thereof;

FIG. 3 is a perspective view from the side opposite to that shown in FIG. 1; and

FIG. 4 is a side elevation thereof.

The rear of the cabinet is plain and unornamented.
